UNITED STATES PATENT OFFICE.

WYNN MEREDITH, OF ALAMEDA, CALIFORNIA, ASSIGNOR TO PETROLEUM RECTIFYING COMPANY, OF SAN FRANCISCO, CALIFORNIA, A CORPORATION OF CALIFORNIA.

CENTRAL CIRCULATING DEHYDRATOR FOR PETROLEUM OILS.

Application filed March 14, 1921. Serial No. 452,389.

To all whom it may concern:

Be it known that I, WYNN MEREDITH, a citizen of the United States, residing at Alameda, county of Alameda, and State of California, have invented a new and useful Improvement Comprising a Central Circulating Dehydrator for Petroleum Oils, of which the following is a specification.

My invention relates to dehydrators for petroleum oils in which the oils are subjected to the action of an electric field for the purpose of causing the water particles carried therein to agglomerate and form large masses which may be settled out by gravity.

It is a well known fact, if a petroleum emulsion is introduced into an electric field, that the small water particles carried therein are caused to coalesce or agglomerate into masses of sufficient size to readily settle out of the oil under the influence of gravity. It is also a well known fact that under certain conditions the water particles may arrange themselves between the electrodes in chains of such size and number that the electrodes are virtually short-circuited and the voltage between the electrodes fall to so low a value that dehydration practically ceases. Certain previous inventors have sought to prevent this excessive chain formation by agitating the emulsion in the electric field by a rotation of the inner electrode.

My invention is designed to provide an agitation and mixing by the natural convection currents in the body of emulsion itself, this action in some cases being assisted by mechanical means.

The principal object of the invention is to provide a novel form of dehydrator having certain advantages which will be set forth more fully hereinafter.

Referring to the drawings which are for illustrative purposes only.

Fig. 1 is a section through one embodiment of my invention.

Fig. 2 is a plan view of same.

Fig. 3 is a section on a plane represented by the line 3—3 of Fig. 1.

Fig. 4 is an enlarged view of a portion of my invention.

Fig. 5 is a diagram of the dehydrator with its associated washing tank.

In the form of the invention illustrated, Fig. 1 is a shell having a flared top 12 in which

insulators 13 are supported on brackets 14. A spider 15 is supported on the insulators 13 and carries a central pipe 20 on which a top plate 21 is carried by means of a flange 22 which is secured to the plate 21 and threaded on the pipe 20. Supported by means of spaced members 25 on the rod 20 is a cylinder 26 carrying an inverted funnel 27, an intermediate plate 28, and a plate 29 which is hereinafter referred to as the lower plate to distinguish it from the upper plate 21. Oil is introduced into the top of the dehydrator through an oil inlet pipe 30 which delivers emulsion into a trough formed by a lip 31 extending completely around the tank which is so levelled that the upper edge of the lip 31 is level and the emulsion spills evenly thereover throughout the lip's entire circumference. A fan 40 driven through beveled gears 41 by means of a shaft 42 is provided in the bottom of the dehydrator, the shaft 42 being driven by a motor 43 or by any other convenient means. Oil is withdrawn from the dehydrator through a pipe 45 and delivered into a wash tank 46 shown in Fig. 5. A transformer is provided having a primary 50 and a secondary 51. The primary 50 is connected to any convenient source of electrical energy, the secondary 51 having one side connected to the tank as shown at 52 and the other side connected to the spider 15 shown at 53. A steam coil 60 is provided in the bottom of the tank 11.

The method of operation is as follows:

The distance between the upper plate 21 and the lower plate 29 may be readily varied by turning the plate 21 on the pipe 20. Since the pipe 20 is threaded and the flange 22 is also threaded, the distance between the two plates 21 and 29 may be varied due to the up and down movement of the plate 21 as it is turned on the pipe 20. A potential being impressed between the points 52 and 53, this potential manifests itself between the edges of the members 21, 27, 28 and 29 and the inner surface of the tank 11. In practice I prefer to make the members 27 and 28 of somewhat smaller diameter than the members 21 and 29 so that there will be some concentration of field at the edges of the plates 21 and 29. The cold emulsion is introduced through the pipe 30, this emulsion flowing in a thin film over the upper edge of the lip 31 and down-

wardly over the inner surface of the tank, the emulsion being somewhat colder than the liquid in the tank 11 which is heated by the steam coil 60. This material in the tank 11 is, of course, partially de-emulsified oil which has been heated by the steam coil 60. This sets up convection currents in the tank 11. These convection currents cause the emulsion to flow downwardly close to the inner wall of the tank 11 and this downwardly flowing oil is replaced with oil rising through the cylinder 26 and flowing outwardly in all directions in a thin stream through the small orifice formed between the plates 21 and 29. These convection currents are greatly assisted by the cone shaped funnel 27. It should be understood that the convection currents mentioned above naturally continue to the bottom of the tank, the oil then being heated by the steam coil 60 and rising vertically. The greater portion of this oil is naturally caught by the funnel which tends to establish the convection currents and these convection currents when once established become quite strong and tend to draw all of the returning oil upwardly into the funnel 37. The oil is thus directed tangentially in all directions against the inner wall of the tank 11 and the dehydrating action takes place in this moving body of oil. In some kinds of oil the natural convection currents in the oil are sufficient to set up proper circulation. In some kinds of oil, however, it is necessary to provide for an artificial circulation. This is readily obtained by means of a fan 40 which sets up a steady stream of oil flowing upwardly in the center of the tank 11, the funnel 27 catching that stream and directing it upwardly through the cylinder 26.

I claim as my invention:

1. In an electrical dehydrator for emulsions, the combination of a hollow cylindrical outer electrode; a hollow cylindrical inner electrode open at the bottom to allow emulsion to pass freely therein; means for directing the emulsion outwardly from the top of said inner electrode, into the space between said electrode; and means for impressing an electrical potential between said inner and outer electrodes.

2. In an electrical dehydrator for emulsions, the combination of a hollow cylindrical outer electrode; a hollow cylindrical inner electrode open at the bottom to allow emulsion to pass freely therein; means for directing the emulsion outwardly from the top of said inner electrode in an evenly distributed flat stream into the space between said electrodes, and means for impressing an electrical potential between said inner and outer electrodes.

3. In an electrical dehydrator for emulsion, the combination of a hollow cylindrical outer electrode; a hollow cylindrical in-

ner electrode open at the bottom to allow emulsion to pass freely therein; a series of disks fixed on the outer surface of said inner electrode; means for directing the emulsion outwardly from the top of said inner electrode into the space between said electrodes and means for impressing an electrical potential between said inner and outer electrodes.

4. In an electrical dehydrator for emulsions, the combination of a hollow cylindrical outer electrode; a hollow cylindrical inner electrode open at the bottom to allow emulsion to pass freely therein; an annular lower plate having the edge of its opening fixed to the top of said cylindrical inner electrode; an imperforate upper circular plate secured above said lower plate and at a small distance therefrom, and means for impressing an electrical potential between said inner and outer electrodes.

5. In an electrical dehydrator for emulsion, the combination of a hollow cylindrical outer electrode; a hollow cylindrical inner electrode open at the bottom to allow emulsion to pass freely therein; a series of disks fixed on the outer surface of said inner electrode; an annular lower plate having the edge of its opening fixed to the top of said cylindrical inner electrode; an imperforate upper circular plate secured above said lower plate and at a small distance therefrom, and means for impressing an electrical potential between said inner and outer electrodes.

6. In an electrical dehydrator for emulsions, the combination of a hollow cylindrical outer electrode; a hollow cylindrical inner electrode open at the bottom to allow emulsion to pass freely therein; means for directing the emulsion outwardly from the top of said inner electrode into the space between said electrodes; mechanical means for forcing emulsion to flow upwardly through said inner electrode, and means for impressing an electrical potential between said inner and outer electrodes.

7. In an electrical dehydrator for emulsion, the combination of a hollow cylindrical outer electrode; a hollow cylindrical inner electrode open at the bottom to allow emulsion to pass freely therein; a series of disks fixed on the outer surface of said inner electrodes; mechanical means for forcing emulsion to flow upwardly through said inner electrode; means for directing the emulsion outwardly from the top of said inner electrode into the space between said electrodes and means for impressing an electrical potential between said inner and outer electrodes.

8. In an electrical dehydrator for emulsions, the combination of a hollow cylindrical outer electrode; a hollow cylindrical inner electrode open at the bottom to allow

emulsion to pass freely therein; an annular lower plate having the edge of its opening fixed to the top of said cylindrical inner electrode; an imperforate upper circular plate secured above said lower plate and at a small distance therefrom; mechanical means for forcing emulsion to flow upwardly through said inner electrode, and means for impressing an electrical potential 10 between said inner and outer electrodes.

9. In an electrical dehydrator for emulsion, the combination of a hollow cylindrical outer electrode; a hollow cylindrical inner electrode open at the bottom to allow emulsion to pass freely therein; a series of disks

fixed on the outer surface of said inner electrode; mechanical means for forcing emulsion to flow upwardly through said inner electrode; an annular lower plate having the edge of its opening fixed to the top of 20 said cylindrical inner electrode; an imperforate upper circular plate secured above said lower plate and at a small distance therefrom, and means for impressing an electrical potential between said inner and outer electrodes. 25

In testimony whereof, I have hereunto set my hand at San Francisco, California, this 1st day of March 1921.

WYNN MEREDITH.
